UNITED STATES PATENT OFFICE.

SAMUEL N. GOODMAN, OF PHILADELPHIA, PENNSYLVANIA, ASSIGNOR TO
FRIEDBERGER-AARON MANUFACTURING COMPANY, OF PHILADELPHIA,
PENNSYLVANIA, A CORPORATION OF PENNSYLVANIA.

DESIGN FOR LACE EDGING.

49,209.

Specification for Design. Patented June 20, 1916.

Application filed April 10, 1916. Serial No. 90,259. Term of patent 7 years.

To all whom it may concern:

Be it known that I, SAMUEL N. GOODMAN, a citizen of the United States, residing in Philadelphia, county of Philadelphia, and State of Pennsylvania, have invented a new, original, and ornamental Design for Lace Edging, of which the following is a specification, reference being had to the accompanying drawings, which form a part thereof.

The drawing is a plan view of a portion of lace edging showing my design.

The same comprises a heading or sewing-on edge *a*, a strip *b* composed of a plurality of longitudinally extending chain threads

united by relatively fine cross threads, a row *c* of ornamental scalloped figures, a strip *d* similar to the strip *b*, and a row *e* of figures similar to row *c*.

I claim—

The ornamental design for a lace edging, as shown and described.

In testimony of which invention, I have hereunto set my hand, at Philadelphia, on this 3rd day of April, A. D. 1916.

SAMUEL N. GOODMAN.
